BERNARD F. HORSTING AND GEORGE C. LEPPA, OF CHICAGO, ILLINOIS

CLIP

Application filed July 31, 1929. Serial No. 382,531.

This invention relates to clips or toggles especially designed for securing leather, hides, pelts, and other sheet like materials to stretching frames.

5 In our co-pending application Serial No. 246,492 we show a clip or toggle for this purpose. In such clip the movable jaw is moved into release position by a thumb piece which is located in the space between the 10 upper ends of the side brackets to which the movable jaw is fulcrumed. This space is no wider than the width of the clip or toggle itself, and as the latter is relatively narrow, it follows that the thumb piece is somewhat difficult to operate, especially by a 15 workman having an unusually wide thumb which will not enter the space to reach the releasing member. This in and of itself is not a serious objection to the clip, but 20 it does make the clip inconvenient of operation by some workman. Having the thumb piece so arranged it is necessary to provide an opening therefor in the top wall of the body member of the clip. This of course 25 weakens the body member and in addition makes the clip more costly because of the punching operation required to make the opening.

The object of our invention is to improve 30 on the clip of the application and we do so by having the releasing member engageable from the rear end of the clip, thereby allowing free and unobstructed access to be had to said member at all times and avoiding the objection referred to in connection 35 with the other clip.

Another object of our invention is to have 40 the body of the clip extend through an opening in the releasing member and thus avoid punching an opening in the body of the clip to weaken it as heretofore.

A further object of our invention is to 45 provide a spring action for the movable jaw and so construct and arrange the action that it passes a dead center to hold the jaw either open or closed as desired.

The invention consists further in the matters hereinafter described and claimed.

In the accompanying drawings:

50 Fig. 1 is a side elevational view of a clip

constructed in accordance with our invention;

Fig. 2 is a longitudinal vertical sectional view taken through the clip on line 2—2 of Fig. 4, the movable jaw of the clip being 55 shown in open position;

Fig. 3 is a similar vertical sectional view showing the movable jaw in closed position and engaging a sheet of material to be stretched;

Fig. 4 is a horizontal sectional view taken on line 4—4 of Fig. 3;

Fig. 5 is an end view of the clip; and

Fig. 6 is a top plan view of the forward part of the upper jaw to show the recesses 60 at the sides there for the brackets to be presently described.

The clip of our invention comprises a one-piece metal body member 1, substantially elongated U-shaped in form and having upwardly extending side flanges 2, 2 integral with the side marginal edges of the flat lower arm 3 of the U. The flanges 2 have upper reduced portions 4, 4 which form brackets and extend above the upper arm 5 of the 75 U on the opposite sides thereof, as shown in Figs. 1 to 3. The brackets 4, where they cross the arm 5, have openings or apertures 6, 6 into which extend tongues 7, 7 at the 80 sides of the arm and made integral therewith. The openings 6 extend above the tongues 7 and are made large enough to receive the ends of a rod 8 which extends across the upper side of the arm 5 between the brackets to connect them together and 85 keep the brackets from spreading away from the arm. The opposite ends of the rod are riveted against the outer sides of the brackets for this purpose. The brackets have forwardly projecting portions 9, 9 at their upper ends, which portions bear edgewise against the upper surface of the arm 5 along its side edges beyond the tongues 7 to connect the arms 3 and 5 together at the front 90 end of the clip and to keep said arms from spreading apart under the spring action provided by the loop 10 in the U at the rear end of the clip.

The arm 5 at the brackets 4 is substantially as wide as the space between the brackets 100

so that the latter may be brought against the side edges of the arm. Beyond the brackets the arm 5 is a trifle wider so that the projections 9 may overlap the arm. Re-5 cesses 11, 11 are provided in the side edges of the arm 5 between the tongues 7 and the widened front portion of the arm to receive the portions of the brackets at the tongues. The forward portion of the arm 5 under the 10 projections 9 constitutes the upper or stationary jaws of the clip and this is directly above the movable jaw 12 to be now referred to.

The movable jaw 12 is provided with trunnions 13, 13 at its lower end to engage in apertures 14, 14 in the flanges 2 adjacent the front end of the clip. The trunnions provide the fulcrum for the jaw 12 and permit it being swung toward and from the stationary or fixed jaws. The jaw 12 is located between the side flanges 2 and has its upper surface transversely serrated so as to prevent slippage of the material 15 engaged between the jaws. The movable jaw is in the shape 25 of an inverted U and being fulcrumed at its lower end, said jaw will be drawn toward the stationary jaw on the outward pull of the material thereon, and thus clamp the material tighter between the jaws.

30 The movable jaw 12 is of a width substantially equal to the distance between the side flanges 2 and has its inner end between the brackets 4 and directed downward toward the lower arm 3 of the clip, as shown in 35 Figs. 2 and 3. The side flanges 2 in their portions at the rear of the openings 14, are pressed outward to provide vertical channels 15', 15', one on the inside of each flange. These channels overlap the rear 40 portions of the openings 14 and extend to the bottom thereof so that the trunnions 13 may be engaged in the openings in assembling the clip.

To move the jaw 12 away from the fixed 45 jaw 5 so as to release the material 15, or open the clip to receive the material, we provide an operating member 16 which is located to the rear of the brackets 4. The member 16 is fulcrumed between the flanges 2 to the rear of the brackets by trunnions 17, 17 which are at the lower end of the member and engage in openings 18, 18 in the flanges 2. The member 16 above the flanges 2 is widened out and provided with a rectangular 55 opening 19 through which the upper arm 5 of the clip extends, as shown in Fig. 5. The opening 19 is made wide enough to permit of free movement of the member 16 as it is swung back and forth in opening and closing the movable jaw 12, and also to allow for maximum movement of the jaw to accommodate any thickness of material to be engaged thereby. The member 16 at its lower end just below the trunnions 17 is provided with a forwardly extending finger 20

which reaches to the inner or free end of the jaw 12 and extends into a slot or opening 21 therein.

Arranged about the finger 20 is a coiled spring 22, which is of the expansion type and bears at its ends against the inner or free end of the jaw 12 and the lower end of the member 16. The fulcrum 17 for the member 16 is above the fulcrum 13 for the jaw 12, the line *a* between the centers of the fulcrums indicating the dead center for the spring action. When the jaw 12 is in clamping position, as shown in Fig. 3, the finger 20 and the spring 22 thereon extend above the dead center line *a*. The upward force of 70 the spring 22 holds the jaw 12 raised and presses it against the stationary jaw 5 or against the material 15 therebetween. The spring also holds the member 16 close to or against the upper surface of the loop 10 and 75 from being accidentally moved upward.

On raising the member 16 to open the jaw 12 to release the material 15 or open the clip to receive the material, the finger 20 is swung downward against the lower edge of the slot 21 and swings the jaw 12 in the same direction. This movement continues until the finger 20 passes below the dead center line *a* and the spring 22 in expanding holds the jaw 12 open and the member 16 raised, as shown in Fig. 2. This prevents the jaw 12 closing on releasing the lifting force on the member 16, and the clip will remain open until it is desired to close it. This enables the clips around the edge of the material being stretched to be opened quickly by merely raising the members 16 and all of the clips will remain open to permit the material to be easily withdrawn therefrom. The flanges 2 at the forward edges of the 100 openings 18 for the trunnions 17 are pressed outward to provide vertical channels 23 which permit the trunnions to be engaged in the openings 18 on assembling the clip.

105 A hook-shaped barb or prong 24 extends downward from the lower arm or base 3 of the clip adjacent its rear end, that is, where the loop 10 joins the base 3. The prong 24 may be formed by stamping it out from the metal of the base 3, in that case, a slot being 110 formed where the metal is displaced to provide the prong, as shown in Figs. 2 and 3. The prong 24 is provided to engage in any one of a number of holes or apertures 25, 25 in the plate 26 of the supporting or stretcher frame as employed in leather stretching devices. A portion of the metal of the base 3 to the rear of the prong 24 is pressed downward to provide a lug or boss 27 in line with the prong and of a length, together with the 115 prong to fit in any of the openings 25. This will give added support to the prong and transfer the stretching strain on the clip to the body thereof.

120 In practice the clips of our invention are 130

engaged with the marginal edge of the hide or other sheet material to be stretched about the outer marginal edge thereof and the prongs 24 of the clips with their bosses 27 are engaged in the appropriate apertures or holes 25 in the plates 26 of the stretching frame. With the flanges 2 extending upward from the lower arm 3 of the clip and with the movable jaw 12 below the fixed one 5, the material to be stretched is held at a considerable distance above the plates 26 of the frame and does not contact therewith. This provides an air circulating space between the material and the plate or plates beneath the same.

The member 16 extends to the rear of the loop 10 and thus free access may be had thereto at all times. There are no parts of the clip structure in the way to interfere with reaching the member to operate it, as heretofore. The loop 10 also provides an opening to receive the finger of the hand operating the clip and thus enables the clip to be readily and easily held while the thumb is used to raise the member 16. The loop where it joins the base 3 is offset above the base to provide a rest or shoulder 28 for the finger of the hand when opening the clip and applying it to the edge of the material to be stretched. The clip is made of relatively heavy gauge metal and is rigid, strong and efficient. It is easily made and may be produced at small expense.

The details of structure and arrangement of parts shown and described may be variously changed and modified without departing from the spirit and scope of our invention.

We claim as our invention:

1. A clip of the character described, comprising a substantially elongated U-shaped body portion open at one end, means connecting the arms of the U together at the open end, a movable jaw carried by one arm and movable toward and from the other arm to close and open the clip, and means for moving said jaw, said means having an operable member which is engageable at the loop end of the clip, said member having an opening through which the body portion of the clip extends.

2. A clip of the character described, comprising a substantially elongated U-shaped body portion at one end, means connecting the arms of the U together at its open end, a movable jaw carried by one arm and movable toward and from the other arm to close and open the clip, and means for moving said jaw, said means including spring means acting to hold the jaw open or closed as it is moved into either of said positions.

3. A clip of the character described, comprising a substantially elongated U-shaped body portion open at one end, means connecting the arms of the U together at its open

end, a movable jaw and an operating member therefor, both fulcrumed between said arms with the fulcrum of the member above that of the jaw, a finger carried by said member and engageable with the jaw for moving the same in the swinging of said member, said finger passing the line of dead center between said fulcrums in the opening and closing of the jaw, and spring means acting to hold the jaw open or closed as the jaw is moved into either of said positions.

4. A clip of the character described, comprising a substantially elongated U-shaped body portion open at one end, means connecting the arms of the U together at its open end, a movable jaw and an operating member therefor, both fulcrumed between said arms with the fulcrum of the member above that of the jaw, a finger carried by said member and engageable with the jaw for moving the same in the swinging of said member, said finger being inclined to the line of dead center passing through said fulcrums and passing said line in the opening and closing of the jaw, and a coiled spring about said finger and acting to hold the jaw open or closed as the jaw is moved into either of said positions.

5. A clip of the character described, comprising an elongated substantially U-shaped body portion open at one end with the arms of the "U" arranged one above the other and extending to and terminating at the open end of the clip, flanges carried by one arm and engaged with the other arm to rigidly connect the arms together, so that one arm may serve as the fixed jaw for the clip, a movable jaw fulcrumed between said flanges adjacent the other arm, and movable toward and from the fixed jaw in the closing and opening of the clip, and means for moving the movable jaw, said means having an operable member which when the jaw is closed extends rearward beyond the loop of the "U" at the rear end of the clip.

6. A clip of the character described, comprising an elongated substantially U-shaped body portion open at one end, flanges carried by one arm of the U and engaged with the other arm to connect the arms together, a movable jaw fulcrumed between said flanges adjacent the one arm and movable toward and from the other arm, an operable member for said jaw, said member being fulcrumed between said flanges to the rear of the jaw and on a level different than that of the fulcrum of the jaw, said member having a finger engageable with said jaw for moving the same and passing the dead center line between the fulcrums in the opening and closing of the jaw, and spring means acting on the jaw to hold it open or closed as the jaw is moved in either of said positions.

7. A clip of the character described, com-

- prising an elongated substantially U-shaped body portion open at one end, side flanges carried by one arm of the U and having reduced portions forming brackets extending across the other arm of the U at the side edges thereof, means extending between and engaged with said brackets for connecting them together, a movable jaw and an operable member therefor fulcrumed between said flanges on opposite sides of said brackets, a finger carried by said member between said flanges and engageable with said jaw for moving the same, and a coiled spring about said finger and pressing against said member and jaw, respectively.
8. A clip of the character described, comprising an elongated substantially U-shaped body portion open at one end, side flanges carried by the lower arm of the U and having reduced portions forming brackets extending across the upper arm of the U at its side edges, a rod extending between and engaged with said brackets above said upper arm for connecting the arms together, a movable jaw and an operable member therefor fulcrumed between said flanges on opposite sides of said brackets, a finger carried by said member between said flanges and engageable with said jaw for moving the same, a coiled spring about said finger and pressing against the member and jaw, respectively, and a prong carried by the lower arm and extending below the same.
9. A clip of the character described, comprising an elongated substantially U-shaped body portion open at one end, means including flanges at the sides of one of the arms of the U for connecting the arms together at the open end of the U, a movable jaw member and an operable member therefor between said flanges and each having trunnions engageable in openings in said flanges, said flanges having channels at the openings so that the trunnions may be engaged therewith when assembling the clip, and spring means acting on said members to hold the jaw member either open or closed.
10. A clip of the character described, comprising an elongated substantially U-shaped body portion open at one end, means connecting the upper and lower arms of the U together at the open end of the clip, a movable jaw member and operable member therefor fulcrumed between said arms with the jaw member movable toward and from the upper arm in the closing and opening of the clip, a prong carried by the lower arm and extending below the same, and a boss on the long arm to transfer the strain on the prong to the lower arm when the clip is in use.
11. A clip of the character described, comprising an elongated substantially U-shaped body portion open at one end, means connecting the upper and lower arms of the

U together at the open end of the clip, a movable jaw member and an operable member therefor fulcrumed between said arms with the jaw member movable toward and from the upper arm in the closing and opening of the clip, and a prong and a boss pressed out of the lower arm and extending below the same, said boss being to the rear of the prong to provide an additional support therefor.

12. A clip of the character described, comprising an elongated substantially U-shaped body portion open at one end, side flanges on the lower arm of the U and having brackets extending across the upper arm, means connecting the brackets together at said upper arm, tongues on the upper arm at said brackets and extending into apertures therein, said brackets having projections engaging over the forward portion of the upper arm, and clamp means including a movable jaw fulcrumed between said flanges and movable toward and from said upper arm.

13. A clip of the character described, comprising upper and lower arms, a loop connecting the arms together at one end, means connecting the arms together at the other end, a movable jaw fulcrumed between said arms and movable toward and from the upper arm in closing and opening the clip, and means for moving said jaw including an operable member fulcrumed between said arms, said member extending toward the loop to be engaged from the rear thereof, said loop where it joins the lower arm being offset upward to provide a rest or shoulder for the finger of the hand when holding the clip.

In testimony whereof we affix our signatures.
